DESIGN FOR A CIGARETTE BOX

George C. De Hart, Los Angeles, Calif.

Application June 19, 1937, Serial No. 69,936

Term of patent 7 years

To all whom it may concern:

Be it known that I, George C. De Hart, a citizen of the United States, residing in the city of Los Angeles, in the county of Los Angeles, and State of California, have invented a new, original, and ornamental Design for a Cigarette Box, of which the following is a specification, reference being had to the accompanying drawing, forming part thereof.

Fig. 1 is a front elevational view of a cigarette box and its cover, showing my new design.

Fig. 2 is a top plan view of the cigarette box; and

Fig. 3 is a rear elevational view thereof.

I claim:

The ornamental design for a cigarette box, substantially as shown.

GEORGE C. DE HART.
